UNITED STATES PATENT OFFICE.

CHARLES S. LEWIS, OF WATERBURY, CONNECTICUT, ASSIGNOR OF ONE-HALF TO WILLIAM E. FULTON, OF SAME PLACE.

FARE-REGISTER.

SPECIFICATION forming part of Letters Patent No. 504,731, dated September 12, 1893.

Application filed January 4, 1893. Serial No. 457,230. (No model.)

To all whom it may concern:

Be it known that I, CHARLES S. LEWIS, a citizen of the United States, residing at Waterbury, in the county of New Haven and State 5 of Connecticut, have invented certain new and useful Improvements in Fare-Registers; and I do hereby declare the following to be a full, clear, and exact description of the invention, such as will enable others skilled in the 10 art to which it appertains to make and use the same.

This invention relates to certain new and useful improvements in fare registers adapted more particularly for use in street cars, omnibuses, and other public conveyances, its object being to provide a machine of this class which shall be simple, accurate, and compact.

In the accompanying drawings, forming a part of this specification, and in which the 20 same letters of reference indicate the same or corresponding parts, Figure 1 is a plan view with the case removed. Fig. 2 is a front elevation. Fig. 3 is a central vertical section. Fig. 4 is an end elevation looking from the 25 left hand of Fig. 1 with the standard omitted. Fig. 5 is a vertical section on the line 5—5 of Fig. 3, looking in the direction of the arrow. Fig. 6 is a partial bottom plan view showing the bell hammer, a part of the bell, and the 30 hammer-operating mechanism. Fig. 7 is a detail side elevation of one of the ratchet wheels of the registering wheels, showing more particularly the manner in which the wire pawls carried by each wheel are pressed 35 into engagement with the adjacent ratchet wheel by means of the detent spring thereof, and Fig. 8 is a detail side elevation of one of the ten-toothed star-wheels located upon each end of the main shaft, the yoke, and the 40 pawl thereof engaging and revolving said star wheel at each upward movement of the operating slide.

In the present invention I employ as the essential characteristics, suitable means where- 45 by the trip register can be reset at will to zero without affecting the totalizing register, by which means an accurate account of the total number of fares collected up to or below the registering capacity of the totalizing register 50 may be kept regardless of the number of trips

or of the number of times the trip register has been reset.

Referring to the drawings and more particularly to Figs. 1, 2, and 3 thereof, 1 denotes the base-plate designed to be secured 55 to the wall of the car or vehicle in the position shown in Fig. 1.

The mechanism is preferably inclosed in a suitable casing to prevent its being interfered with, or the collection of dust thereon, 60 which would tend to interfere with its operation. This casing, which it is not deemed necessary to illustrate, is provided with sight slots through which numbers registered by the trip and totalizing registers may be viewed 65 from without by the operator and occupants of the vehicle. Upon the base-plate 1, above referred to, is a slide-bar 2 designed to move thereon and constituting the prime-mover of the register. This slide is held in place and 70 guided in its movement by a housing 3, and is operated by pull-cords 4 attached to the upper end thereof and extending to different points within the vehicle, easily accessible to the operator or conductor.

Projecting from the base-plate near the ends thereof are standards 5 and 6, which, taken in connection with the base-plate and standards 17, 18, and 19 presently described, 75 constitute the frame for supporting the mech- 80 anism of the machine.

7 is the main shaft of the machine supported at its ends in the standards 5 and 6 and parallel to the base-plate 1. Upon this shaft the registering wheels, comprising the 85 trip and the totalizing registers, are supported.

The numerals 10 and 11 indicate respectively the units and the tens registering wheels of the trip register, each of which is provided on its periphery with numerals from 0 to 9 90 arranged in order of their numeric value. The units wheel 10 is secured to or integral with a sleeve 8 which is keyed on the shaft 7, while the tens wheel 11 is journaled on this sleeve 8 adjacent to the units wheel and in 95 such manner as to permit its independent rotation with relation thereto. These wheels 10 and 11 have each secured thereto or integral therewith ten-toothed ratchet wheels 13 and 14 respectively, engaged by pawls 25 and 100

24, see Fig. 1, rigidly fixed on shaft 20, for retaining the registering wheels 10 and 11 against accidental movement.

The registering wheels 10 and 11 are formed 5 hollow and each contains a spring 15, the ends of which are attached to the hubs of the wheels and to posts 16, shown in Fig. 4, in such manner that at every forward movement of their respective registering wheels 10 the tension of the springs is increased. Thus it will be seen that when it is desired to reset these registering wheels 10 and 11 to zero, it may be accomplished by releasing the wheels from the pawls through mechanism 15 presently described, and allowing the springs to act on the wheels, which action will return them to their initial position.

The numerals 17, 18, and 19 (see Fig. 2) denote standards projecting from the base- 20 plate 1.

Between and in the standards 17 and 18 is journaled a short shaft 20, and between and in the standards 18 and 19 is journaled in like manner a similar shaft 21, said shafts, as appears in Fig. 4, being adjacent and parallel to the peripheries of the registering wheels of the trip and the totalizing registers.

The register wheels 10 and 11 have secured thereto ten-toothed ratchet wheels 9 and 12 30 respectively, located at the left of these wheels and adjacent to each other. These ratchet wheels are engaged by detent springs 22 and 23 secured to a sleeve 23^a (see Fig. 2) mounted loosely on the shaft 20, for retaining the 35 wheels against accidental movement, and for the purpose presently described.

Secured rigidly on the shaft 20 is a collar 20^a having a pin 20^b projecting from one side thereof, which engages a slot 23^b in the loose 40 sleeve 23^a. The object of this construction is to allow the shaft 20 and the lever 31 which is secured rigidly thereon, its upper end normally engaging the cam 30 of the arm 26^a, to be rocked without affecting the detent 45 springs 22 and 23 and thus keep them always in engagement with their respective ratchet wheels when the said shaft and lever are operated through the slide bar 2. This will be obvious from the fact that the pin 20^b is allowed to play in the slot 23^b in the sleeve 23^a, 50 as will also the object of this construction by reading what immediately follows.

35 (Figs. 1, 2, and 7) is a spring wire pawl secured on the ratchet wheel 9 and having 55 its outer end provided with a toe which overhangs the ratchet wheel 12 and is normally out of contact therewith. This toe engages a tooth of the ratchet wheel 12 once in every complete revolution of the ratchet wheel 9 by 60 reason of its being forced between the detent spring 23 and the periphery of said wheel 12 and hence into engagement with one of the teeth on said wheel. At the next movement of the ratchet wheel 9, the spring wire pawl 65 35, and the ratchet wheel 12, the pawl being in engagement therewith, are moved simultaneously a corresponding distance. This

movement carries the pawl 35 out of engagement with the detent spring 23, in consequence of which it springs back to its normal 70 position out of engagement with the ratchet wheel 12, and does not again engage it until it performs a complete revolution and is brought again under the action of the detent spring 23. Thus it will be seen that the tens register 75 wheel 11 is caused to move only one step forward to every ten, or once at every complete revolution of the units wheel 10.

The numeral 26 designates a yoke composed of two parallel arms 26^a and a connecting bar 27 (see Fig. 3), extending beneath and parallel to the peripheries of the registering wheels and connecting the arms 26^a. The arms 26^a are journaled at their upper ends on the main shaft 7, and these upper ends are 85 formed into cams 30 and 45 (see Figs. 4 and 8 respectively). The cam 30 at the left hand end of the machine is engaged by a lever 31 secured on the shaft 20, and held normally in engagement with the concave portion of 90 the cam by means of a spring 32 secured to a pin 32^a of the rod 20 and to a projection 32^b on the base plate 1. Secured to an offset portion 26^b of the arm 26^a is a spring pressed pawl 26^c normally held in engagement with 95 the ratchet wheel 9 of the registering wheel 10, this pawl being allowed to drag over the teeth of the wheel during the forward movement of the yoke 26 and engage the next succeeding tooth of said wheel, which it moves 100 one step as the yoke is returned to its normal position. The bar 27 of the yoke 26 is engaged by the arms 28 of the slide or prime-mover 2 and consequently the movement thereof is effected through the slide 2, which 105 moves in opposition to a spring 33 secured to the base-plate 1 and to a depending lug 62 of the slide 2, as is clearly shown in Fig. 5, and which will be more fully described presently. From this it will be seen that when the yoke 110 26 is rocked forward through the slide or prime-mover 2 the shaft 20 will be revolved in an opposite direction to the movement of the yoke by the action of the cam 30 of the arm 26^a on the lever 31, and consequently the pawls 115 24 and 25 will be thrown out of engagement with the ratchet wheels 13 and 14 independent of the detent springs 22 and 23 which remain stationary, allowing said ratchet wheels to rotate freely, until the yoke is returned to 120 its normal position, when the said pawls are again thrown into engagement with their respective ratchet wheels, locking them against movement until the yoke is again moved by the slide 2.

The numerals 36, 37, 38, and 39 denote the registering wheels of the totalizing register. These wheels are each provided with numerals from 0 to 9 on their peripheries, arranged in the order of their numeric value, and are 130 loosely mounted on the main shaft 7 to the right of the trip registering wheels 10 and 11.

36 is the units wheel of the totalizing register wheels and carries a ten-toothed ratchet

wheel 40 arranged near one end of the main shaft 7. The shaft 21 journaled in the standards 18 and 19 of the base plate, carries a lever 42 of the same construction and for the 5 same purpose as the lever 31 at the opposite end of the machine.

43 are detent pawls engaging the ratchet wheels 44 on each of the registering wheels 36, 37, 38, and 39, and carried on the shaft 21, the 10 operation, construction and function of which being the same with reference to the totalizing register wheels as the pawls 24 and 25 have with reference to the trip registering wheels 10 and 11.

15 The arms 26^a (at the right hand end of the machine) of the yoke 26 likewise is formed cam-shaped at its upper end as seen at 45, (Fig. 8) and is engaged by the lever 42 of the shaft 21 upon which it acts in the same manner and simultaneously with the lever 31 and shaft 20. A spring 42^a (see Fig. 1) is secured to said lever 42 and to the base plate for holding the former always in contact with the cam 45.

25 The arm 26^b carries a spring-pressed pawl 41 identical in construction and arrangement with the pawl 26^c, which pawl 41 engages and operates the ratchet wheel 40 as the pawl 26^c operates the ratchet wheel 9 of the units wheel 10, and turns the units wheel 36 of the totalizing register.

From the above description it will be seen that the mechanism for operating the trip and totalizing registers is identical in construction and operation, the units wheels of both registers being operated simultaneously by the slide 2 through the yoke 26.

The units wheel 36 is mounted rigidly on a long sleeve 46 or is integral therewith, the 40 other end of which sleeve bears a ten-toothed wheel 47. The tens wheel 37 is mounted rigidly on a similar sleeve 48 but shorter than the sleeve 46, and is journaled thereon, the outer extremity bearing a ten-toothed wheel 49 arranged to the right of and adjacent to the wheel 47. The hundreds wheel 38 is mounted rigidly upon a shorter sleeve 50 than that of the tens wheel, which is journaled upon the sleeve 48, and bears upon its end a 45 ten-toothed wheel 51 arranged to the right of and adjacent to the wheel 49. Upon the outside of the sleeve 50 is journaled the thousands wheel 39, free to rotate thereon. The hub of this wheel bears another ten-toothed wheel 52 arranged adjacent to the wheel 51. All of 55 these toothed wheels are of the same diameter and each of them necessarily travels with its registering wheel, being integral therewith. Each of these toothed wheels 47, 49, 51, and 52 is provided with a spring wire pawl 35^a (see Figs. 2 and 3) similarly constructed and operated in the same manner as the pawl 35 previously described, they being pressed into engagement at proper intervals by the detent 60 springs 54 by which each toothed wheel is engaged and in the manner illustrated in Fig. 7. From this construction it will be seen that

the tens-wheel will be moved only one step to each ten of the units-wheel, the hundreds wheel one step to each ten of the tens-wheel, 70 or to every hundred of the units-wheel, and the thousands-wheel one step to every ten of the hundreds-wheel.

At each registration of a fare a bell 55 is caused to ring. This bell is attached to the 75 reverse side of the base plate 1 from that on which the registering mechanism is mounted.

The mechanism whereby the ringing of the bell is effected is clearly illustrated in Figs. 5 and 6, and consists of a hub 56 having integral therewith two oppositely-disposed arms 57 and 58, and a bell-striking lever 59 on the end of which the bell hammer 60 is disposed. The arm 57 extends over a slot 34 in the base plate 1 and is in the line of movement of the 80 depending lug 62 pivoted to the slide 2 at 63, and extending through the slot 34, so that when the slide 2 is pulled upward the lug 62 will engage the arm 57 and carry it in the same direction until it reaches a point where 85 it is allowed to spring past the lug and back to its normal position. This return movement of the arm 57 is effected by a spring 63^a attached to the arm 58 and to the base plate 1, and causes the bell hammer 60 to be thrown 90 suddenly against the bell 55. Upon the return of the slide 2 to its normal position by the spring 33 previously described, the lug 62 will drag over the arm 57 without affecting it, by reason of its being pivoted at 63 and being 95 capable of movement in this one direction.

To effect the resetting of the trip register wheels 10 and 11 to zero and to allow the springs 15 to be free to act thereon, I employ a releasing slide 64 mounted on the left hand 100 end surface of the base plate 1. This slide is provided with lugs 65 and 66, the former of which projects from the upper face of the slide and engages the tail piece 26^d of the pawl 26^c, and the latter projects through a 110 slot 66^a (see Figs. 2 and 4) in the base plate 1 and engages the lower ends of the detent springs 22 and 23 which extend through the base plate 1 and project from the rear thereof. These springs which are secured rigidly on 115 the loose sleeve 23^a, are held normally in engagement with the ratchet wheels 9 and 12, as has been described by springs 72 secured thereto and to the base plate 1, (Fig. 4.)

The lower end of the slide 64 is provided 120 with a guide slot 67, see Fig. 1, which is engaged by a stud 68, to limit the downward movement of the slide, while the other or upper end of the said slide is pivotally connected by means of a pin 69 to a projection 70 of the 125 handle-lever 71, which lever in turn is pivoted by means of a stud 71^a to the base plate 1. This mechanism brings the releasing mechanism directly under the control of the releasing slide 64, which when actuated by the 130 hand-lever 71 will forcibly engage the lugs 65 and 66 with the pawl 26 and the detent springs 22 and 23 respectively, throwing them out of engagement with the wheels 10 and 11, where-

upon said wheels will be returned to zero by the stored-up tension of the springs 15. When these detent springs are disengaged from their respective ratchet wheels through the releasing slide, the sleeve 23^a in which said springs are secured, is rocked by reason of the said springs being secured thereon, a greater distance than the length of the slot 23^b therein, and the pin 20^b on the collar is engaged by the 10 upper side of the said slot against which it normally rests, in consequence of which the shaft 20 and its detent pawls 24 and 25 are rocked with the sleeve 23^a and the latter thrown out of engagement with their ratchet wheels simultaneously with the detent springs 22 and 23. From this it will be seen that the detent springs 22, 23, 24, and 25 and the pawl 26^c may be operated and thrown out of engagement with their respective wheels simultaneously only by the 15 action of the releasing slide 64 thereon. In the event of the springs 15 failing to act on the trip registering wheels 10 and 11, they may be returned to their initial positions, by turning the handle 7^a of the shaft 7 which, owing to the sleeve 8 being keyed thereon, allows the trip registering wheels to be turned back.

The operation of the fare register is as follows: Supposing all of the wheels of the totalizing and the trip registers at zero, the 20 slide 2 will operate the mechanism heretofore described and cause a simultaneous registering of the units wheels 10 and 36 of each of the series situated one on each side of said slide bar. The car to which the device is attached having completed its first round-trip, the total number of fares will be registered both on the trip and the totalizing wheels. This number will not, of course, exceed 99, but usually less than this number will amply 25 suffice for an ordinary trip. The wheels of the trip register will then be returned to zero without affecting the wheels of the totalizing register, by means of the releasing or tripping mechanism heretofore referred to. Again 30 starting the car with the wheels 10 and 11 at zero these wheels will at the completion of the trip give a correct and instantaneous reading of the amount of fares taken, while at the same time the total of that trip and 35 the preceding ones are registered on the totalizing wheels. It will be readily understood that the capacity of the trip register wheels situated at the left of the slide bar 2 may be increased by adding additional wheels 40 thereto.

Without limiting myself to the precise construction and arrangement of parts shown and described, I claim—

1. In a fare register, the combination of the 45 trip register wheels, the ratchet and toothed wheels secured thereto, the spring wire pawl on said toothed wheel designed to engage the adjacent ratchet wheel, the main shaft on which said register wheels are mounted, the 50 yoke pivoted on said main shaft having the upper ends of its parallel arms cam-shaped, the actuating pawl secured on said yoke, the

supplementary shaft arranged adjacent to the register wheels and carrying a lever which engages the cam on the yoke, the pawls secured on said shaft, and a sleeve supported loosely thereon provided with a slot, detent springs secured to the loose sleeve, a collar fixed rigidly to the supplementary shaft and carrying a pin which engages the slot in the 55 said loose sleeve, and a slide or prime mover connected to the yoke for imparting an oscillatory movement thereto, substantially as described.

2. In a fare register, the combination of the 60 trip register wheels, the ratchet and toothed wheels secured thereto, the spring wire pawl carried by said toothed wheel and designed to engage the adjacent ratchet wheel, the main shaft on which said register wheels are 65 mounted, the yoke pivoted on said shaft and having the upper ends of its parallel arms cam-shaped, the actuating pawl secured on said yoke, the supplementary shaft arranged adjacent to trip register wheels and carrying 70 a lever which engages the cam of the yoke and pawls and detent springs which engage the ratchet and toothed wheels of the trip register, a slide or prime-mover connected to the yoke, through which an oscillatory movement is imparted thereto, and means whereby 75 the pawls on the supplementary shaft may be thrown out of engagement with their respective wheels independent of the detent springs on said shaft, substantially as described.

3. In a fare register, the combination of the 80 trip register wheels and their shaft, the toothed wheels secured one to each register wheel and arranged adjacent to each other, the spring wire pawl carried on the toothed 85 wheel of the units register wheel and having its end bent to overhang the adjacent or tens toothed wheel, the detent springs engaging said toothed wheels and arranged in the path of movement of the spring wire pawl, and 90 means for imparting a step by step rotary movement to the units toothed wheel, substantially as described.

4. In a fare register, the combination of the 95 trip and the totalizing register wheels, the ratchet wheels secured thereto, the main shaft on which said register wheels are mounted, the yoke having its parallel arms cam-shaped and journaled on the main shaft, pawls secured on the arms of said yoke and engaging 100 the ratchet wheels of the units wheel of each register, the supplementary shafts journaled adjacent to said register wheels, levers and pawls secured on said shafts engaging the cams on the yoke, and the ratchet wheels on 105 the register wheels respectively, and a slide connected to said yoke for imparting an oscillatory movement thereto, substantially as described.

5. In a fare register, the combination of the 110 trip and totalizing register wheels, the ratchet and toothed wheels secured thereto, the main shaft on which said register wheels are journaled, the spring wire pawls secured on said 115

- toothed wheels and overhanging the adjacent wheels, the detent springs engaging said toothed wheels and arranged in the path of movement of the spring wire pawls, the yoke having its arms journaled on the main shaft, the pawls carried thereon, and engaging the toothed wheels of the units wheels of both registers, the detent pawls supported adjacent to the registering wheels and engaging the toothed wheels thereof, and the slide or prime mover connected to the yoke for imparting an oscillatory movement thereto, substantially as described.
6. In a fare register, the combination of the trip register wheels, the ratchet and the toothed wheels secured thereto, the spring wire pawl carried on said toothed wheel and designed to engage the adjacent ratchet wheel, the main shaft on which said wheels are journaled, the yoke pivoted on said main shaft, and carrying the actuating pawl, the supplementary shaft arranged adjacent to the register wheels, the pawls and detent springs secured thereon and engaging the ratchet and toothed wheels of the register wheels respectively, and connections between said yoke and supplementary shaft, whereby when the former is rocked the pawls on the latter are thrown out of engagement with the respective ratchet wheels, the releasing slide, having lugs thereon engaging the pawl on the yoke and the detent springs on the supplementary shaft, the spring connected to said detent springs and to the base-plate, and the pivoted handle bar connected to said releasing slide, substantially as described.
7. In a fare register, the combination of the trip register wheels, the ratchet and the toothed wheels secured thereto, the springs connected to each of the register wheels and to the frame of the machine, the main shaft on which the register wheels are journaled, the yoke pivoted on said main shaft and carrying the actuating pawl, the supplementary shaft arranged adjacent to the register wheels, the pawls and detents springs secured thereon and engaging the ratchet and the toothed wheels of the register wheels respectively, the releasing slide having lugs thereon engaging the pawl on the yoke and the detent springs on the supplementary shaft, the spring connected to said detent springs and to the base plate and the pivoted handle-bar connected to said releasing slide, substantially as described.
8. In a fare register, the combination of the trip and the totalizing register wheels, the toothed and ratchet wheels secured to said wheels, the main shaft on which the register wheels are journaled, the yoke having the upper ends of its parallel arms cam-shaped and journaled on the main shaft, the actuating pawls on said arms, the slide or prime-mover connected to the yoke, the supplementary shafts one for each register, journaled adjacent and parallel to the register wheels, the levers and pawls on each of said shafts engaging the cams on the arms of the yoke and the ratchet wheels on the register wheels respectively, the spring wire pawls on the toothed wheels of the register wheels, the detent springs in engagement with said wheels, the pivoted handle bar and the releasing slide having lugs thereon engaging the actuating pawls of the trip register and the detent springs thereof, substantially as described.
9. In a fare register, the combination of the trip and the totalizing register wheels, said trip register wheels having springs secured thereto and connected in such manner as to store up force as the trip register wheels are revolved, and for returning them to their initial position when released, the toothed and ratchet wheel secured to said wheels, the main shaft on which the register wheels are journaled, the yoke having the upper end of its parallel arms cam-shaped, the actuating pawls on said arms, the slide or prime-mover connected to the yoke, the supplementary shafts, one for each register, journaled adjacent and parallel to the register wheels, the levers and pawls on each of said shafts engaging the cams on the arms of the yoke and the ratchet wheels on the register wheels respectively, the spring wire pawls on the toothed wheels of the register wheels, the detent springs in engagement with said wheels, the pivoted handle bar and the releasing slide having lugs thereon engaging the actuating pawls of the trip register and the detent springs thereof, substantially as described.
10. In a fare register, the combination of the trip registering wheels 10 and 11, the totalizing register wheels 36, 37, 38, and 39 journaled upon the shaft 7, and upon their respective hubs, pawls engaging the ratchet wheels on said register wheels, toothed wheels mounted upon the projecting hubs of each of the register wheels, spring wire pawls on each of the register wheels, spring wire pawls on each of said wheels resting normally out of engagement therewith, detent springs engaging said toothed wheels and the spring wire pawls at proper intervals, the yoke 26 carrying the pawls to actuate the ratchet wheels 9 and 40 of the units wheel of the trip and the totalizing registers respectively, the slide 2 engaging the yoke 26, springs 15 arranged on each of the trip register wheels, the releasing slide 115 64 having lugs thereon engaging the actuating pawl of the units wheel of the trip register, and the detent springs 22 and 23 for throwing them out of engagement with said wheels, to permit the return of the trip registering wheels to their initial position, substantially as described.
11. In a fare register, the combination of the trip and totalizing register wheels, the shaft on which said wheels are journaled, the yoke, the slide or prime-mover, and intermediate mechanism between the yoke and the said register wheels for imparting movement thereto, the pivoted lug on the slide or prime-mover, the spring connected to the base-plate, the bell and its hammer, the pivoted hammer-bar and its integral arms, one of which overlies the path of movement of the lug on the slide, and the spring attached to the base-

plate and to the other arm for returning the hammer-bar to its normal position, substantially as described.

12. In a fare register, the combination of 5 the trip registering wheels and their shaft, the ratchet and toothed wheels secured to said wheels, the spring wire pawl carried on the toothed wheel of the units registering wheel and adapted to engage the adjacent toothed 10 wheel of the tens registering wheels, the pawls and detent springs engaging the ratchet wheels and the toothed wheels respectively, and means whereby a step by step rotary movement is imparted to the toothed wheel 15 and the pawls disengaged from their ratchet wheels at each movement independent of the detent springs, substantially as described.

13. In a fare register, the combination of 10 the trip registering wheels and their shaft, 20 the springs secured to said wheels and con-

nected in such manner as to store up force as the register wheels are revolved, and for returning them to their initial position when released, the toothed and ratchet wheels secured to said trip registering wheels, the yoke 25 journaled on the main shaft and carrying a pawl which engages one of the toothed wheels, the pawls and detent springs engaging the ratchet and toothed wheels respectively, and means whereby the pawls and detent springs 30 engaging said wheels are disengaged therefrom simultaneously to release the springs of the trip registering wheels, substantially as described.

In testimony whereof I affix my signature in 35 presence of two witnesses.

CHARLES S. LEWIS.
